(57) CLAIM

We claim the ornamental design for a stocking cap resembling a sports jersey, as shown and described.

DESCRIPTION

FIG. 1 is a front elevational view of a stocking cap resembling a sports jersey showing our new design;
FIG. 2 is a rear elevational view thereof;
FIG. 3 is a right side view thereof; the left side being a mirror image;
FIG. 4 is a top plan view thereof; and,
FIG. 5 is a bottom plan view thereof.
The elements shown in finely incremented broken lines form no part of the invention.
